LEROY C. DOANE, OF MERIDEN, CONNECTICUT, ASSIGNOR TO THE MILLER COMPANY, OF MERIDEN, CONNECTICUT, A CORPORATION OF CONNECTICUT

SHADE HOLDER

Application filed May 27, 1925. Serial No. 33,089.

The present invention relates to shade holders and is more particularly directed toward a shade holder suitable for holding a glass shade or the like from the top of an electric candle, or from an electric lamp socket.

The present invention contemplates a form of shade holder which has suitable means for mounting it outside a lamp socket. In some forms of the invention this mounting means is such as to cooperate with an electric candle sleeve while in other forms of the invention it is arranged so as to cooperate with the brass shell of an ordinary lamp socket.

The accompanying drawings show for purposes of illustrating the invention several of the many possible embodiments in which the present invention may take form, it being understood that the drawings are merely illustrative of the invention, rather than limiting the same.

In these drawings:

Fig. 1 is a sectional view of an electric candle provided with one form of shade support;

Fig. 2 is a perspective view of the shade support of Fig. 1; and

Fig. 3 is a sectional view of a modified form of shade support showing it adapted for use with a lamp socket.

According to the showing in Figs. 1 and 2, this form of the shade holder, is made out of a sheet metal stamping which has a tubular portion 10 adapted to fit inside the fiber sleeve 11 of the electric candle. The upper end of the stamping is flanged outwardly as indicated at 12 and is then drawn downwardly as indicated at 13 to provide a short tubular or cylindrical portion 14 which is adapted to fit inside the hole of a glass shade S. The stamping is then extended outwardly as indicated at 15, and a number of prongs 16 are struck out from the material of the stamping so as to stand vertically as indicated in dotted lines in the left of Figs. 1 and 2. After the shade S has been passed into position these prongs are bent outwardly as indicated. In order to insulate the metal sleeve from the contacts of the lamp socket, a fiber sleeve 17 is carried inside the metal sleeve. These parts may be held together by glue, if desired.

When the lamp is removed from the socket

one is able to remove the shade and holder as the parts are comparatively loose.

According to the form of the invention shown in Fig. 3 the metal sleeve 10' is provided with threads 20 adapted to cooperate with the threads 21 on the shell of an ordinary brass lamp socket. The upper end of the stamping may be provided with flanges and prongs similar to those above described, so that the shade may be held in place.

It is obvious that the invention may be embodied in many forms and constructions and I wish it to be understood that the particular forms shown and described are but a few of the many forms. Various modifications and changes being possible, I do not in any way limit myself with respect thereto.

I claim:

1. A shade holder for supporting a shade from the top of an electric candle or the like, said holder being in the form of a sheet metal ring having an outwardly directed flange at the end, said flange having an offset peripheral portion, and prongs struck out of the flange and being capable of being bent to a position to hold a shade against the offset peripheral portion.

2. A shade holder for supporting a shade from the top of an electric candle or the like, said holder being in the form of a sheet metal sleeve having a tubular portion and an outwardly directed flange at the end, said flange having an offset peripheral portion, and prongs struck out of the flange and being capable of being bent to a position to hold a shade against the offset peripheral portion, and means associated with the tubular portion of the stamping for mounting it about a lamp socket.

3. A shade holder for supporting a shade from the top of an electric candle or the like, said holder being in the form of a sheet metal sleeve having a tubular portion and an outwardly directed flange at the end, said flange having an offset peripheral portion, and prongs struck out of the flange and being capable of being bent to a position to hold a shade against the offset peripheral portion, and an insulating sleeve carried inside the tubular portion of the stamping.

4. A metal stamping for shade holders, having a short cylindrical portion, an outwardly directed flange at one end and an inwardly directed flange at the other, a plurality of prongs struck out of the material of the inner flange and foldable into a position spaced from the outer flange and adapted to hold a shade therebetween, a longer tubular portion extending from the inwardly directed flange and adapted to fit inside a candle sleeve, and an insulating sleeve carried inside the tubular portion whereby the stamping may be insulated from a lamp socket in the candle sleeve.
- 10 5. The combination with an electric candle having a candle sleeve adapted to surround a lamp socket, of a shade support having a tubular metallic portion fitting inside the candle sleeve, a flange resting on top of the candle sleeve, and a shade supporting shelf carried by the flange.
- 15 6. The combination with an electric candle having a candle sleeve adapted to surround a lamp socket, of a shade support having a tubular metallic portion fitting inside the candle sleeve, a flange resting on top of the candle sleeve, and a shade supporting shelf carried by the flange, and an insulating sleeve extending downwardly within the tubular portion of the shade support.

Signed at Meriden, in the county of New Haven and State of Connecticut, this 25 day of May, 1925.

LEROY C. DOANE.
